EDWIN A. WEBSTER, OF GROVELAND, MASSACHUSETTS, ASSIGNOR TO HAVERHILL SHOE MACHINERY CO., OF HAVERHILL, MASSACHUSETTS, A CORPORATION OF MAINE.

SOLE-CHANNELING MACHINE.

1,028,509.

Specification of Letters Patent.

Patented June 4, 1912.

Application filed October 24, 1907, Serial No. 398,909. Renewed February 17, 1912. Serial No. 678,412.

To all whom it may concern:

Be it known that I, EDWIN A. WEBSTER, of Groveland, county of Essex, State of Massachusetts, have invented an Improvement 5 in Sole-Channeling Machines, of which the following description, in connection with the accompanying drawings, is a specification, like characters on the drawings representing like parts.

10 This invention particularly relates to certain improvements in the feeding mechanism or means for forcing the sole into engagement with the cutting-devices of a sole channeling machine.

15 It is practically necessary, in channeling shoes, to perform the operation without injury to the bottom or grain side of the sole. For this reason not only cannot a toothed feed wheel for the grain side of the sole be employed, but even a knurled or corrugated 20 feeding device may not be employed, as it leaves distinct impressions in the sole, or cuts or lacerates it, so that, in either event it is practically impossible to obliterate the 25 results of the operation, and at the same time produce a uniform finish on the sole.

It is the usual practice to channel soles when in temper, or moist, and this causes 30 them to be slippery on the grain side, and especially so when too moist, or when the sole contains glucose, or similar foreign matter, so that an ordinary smooth-faced metal roll has practically no positive feeding effect whatever, and almost might as well be 35 an idler.

It has been found that, in practice, an engagement sufficiently strong to feed the sole 40 against an ordinary stationary channeling knife cannot be secured with an ordinary knurled or serrated upper feed roll and an ordinary smooth-faced under roll, so that the highly objectionable toothed feed wheel has been universally employed, in such instances, for the upper side of the sole.

45 The object of my invention is to provide, in a sole-channeling machine, a form of feeding device for engagement with the grain side of the sole, which, when acting in conjunction with an ordinary knurled or corrugated feed wheel, will feed the sole with 50

sufficient force to enable a stationary channeling knife to perform the channeling operation without injury to the grain side of the sole. I accomplish this object by providing a feeding device for the grain side of 55 the sole which comprises a feeding portion composed of a solid mass of abrasive material provided with an even, or unindented, but abrasive, sole-engaging face, which is adapted to engage the grain surface of the 60 sole with a strong frictional contact, without injury thereto, and a sole-supporting portion having a smooth, non-abrasive face, said faces being continuously arranged, so that consequential injury of the grain surface by the abrasive portion is prevented by 65 the supporting portion.

For a more complete disclosure of my invention, reference is made to the accompanying drawings in which; 70

Figure 1 is a front elevation of the sole-engaging members of a sole channeling machine provided with my invention. Fig. 2 is an end view of the feed rolls. Fig. 3 is a sectional view on the line 3—3 of Fig. 2. 75 Figs. 4 and 5 are respectively central sectional and plan views of a modified form of my invention.

The channel forming devices shown comprise the stationary knife *a* and the rotary 80 cutter *b* disposed at opposite sides of the upper feed roll *c*, said roll having a corrugated or knurled surface, which will not injure the substance of the sole between the knife and cutter. 85

The lower feed roll is preferably in form of a cylinder of materially greater length than the upper roll, and comprises an annular wheel *d* having a cylindrical, sole-engaging and feeding face, and composed of 90 an abrasive substance, such as emery, closely compacted together into a solid mass, such as is ordinarily used in grinding metal, an ordinary emery or carborundum wheel being preferably employed. The wheel *d* is preferably mounted on a metal sleeve *e*, and is clamped between a flange or disk *e'*, integral with one end of said sleeve and a disk *f*, which is threaded on the opposite end of the sleeve *e*, said disks *e'*, *f*, and said wheel 95 *d* being 100

5 *d* all being of the same diameter, and the ends of the wheel and the engaging sides of the disks being flat, so the disks bear firmly against the ends of the wheel at and adjacent the peripheries thereof. The peripheries of the disks *e'*, *f* are smooth or non-abrasive and formed to provide sole-engaging and supporting faces which are continuous with the sole-engaging face of the wheel, 10 the outer or opposite corners of the disks, from the wheel being rounded, so as not to cut or mark the sole when in use.

15 As the wheel *c* presses the sole against roll *d*, a strong frictional engagement is caused between the sole and the wheel, so that, when it is rotated, it will feed the sole past the channel cutting devices. As the wheel *d* is of fine granular or gritty material, it will not indent or cut the leather, 20 and, as it is of substantially the same character as the substance subsequently used on the sole in the buffing operation, if it should slip on the sole, it will merely have a similar action thereon to that of the buffing operation, so that it will not cause any 25 marks thereon which will not blend when the sole is buffed. The result is that the sole is fed under all conditions without practical injury thereto either on the outer 30 or inner side, so that the labor of finishing will not be interfered with, an otherwise unnecessary amount of leather will not have to be buffed off, and the appearance of the sole when finished, will be equal to that 35 when the ordinary smooth feed roll is employed. The frictional engagement of the gritty or granular engaging surface is so strong that there is no appreciable slipping of the wheel *d* on the sole under ordinary 40 conditions, and, in case there should be any slipping, only a slight surface abrasion would be caused, as the clamping disks at the ends of the wheel will support the sole, so as to prevent the wheel from digging 45 into it. As the disks are clamped against the ends of the wheel at its periphery, they act to protect the corners thereof and support the same, so that it will not be broken or chipped. The frictional qualities of the 50 wheel will not be impaired by wear although, in practice, the wearing thereof is inappreciable.

55 In Figs. 4 and 5 I show the application of my invention to the circular table feed commonly employed. In this form a circular metal holder *g* is provided having a cup in its upper side in which a slightly conical shaped disk *d'* of emery, or other granular material, as previously described, is seated, 60 said disk being secured in place by a central bolt *i*. The edges of the cup or holder are also continuous with the sole-engaging and feeding surface of the emery disk, as in the form of my invention before described, so 65 that a support is provided for the edges of

the disk and a sole-supporting surface is provided at one side of said feeding surface. With this form of feeding device the operation is substantially the same as that previously described. It will be apparent 70 that, as the disks, *e'*, *f*, in the form of my invention shown in Figs. 1 to 3, and the cup-shaped holder *g*, in the form shown in Figs. 4 and 5, are both driven with the emery mass *d*, or *d'*, they will also have a 75 feeding action in addition to the functions thereof already described.

Having thus described my invention, what I claim as new and desire to secure by Letters Patent is:—

80 1. In a sole channeling machine, a feeding device for the grain side of the sole having a sole feeding portion composed of a rigid, closely compacted mass of emery, or similar abrasive material, and a non-abrasive, sole-supporting portion at one side thereof, said feeding portion having an abrasive, sole-engaging face and said sole-supporting portion having a non-abrasive, sole-supporting face, said faces being continuously arranged with relation to each other, substantially as described.

85 2. In a sole-channeling machine a pair of feeding devices adapted to be pressed against the opposite sides of the sole, the feeding device for the grain side thereof having a sole-feeding portion composed of a rigid, closely compacted mass of emery, or similar abrasive material, and a sole-supporting portion of non-abrasive material, said portions having unindented, 90 continuously arranged, and respectively, abrasive and non-abrasive sole-engaging faces, substantially as described.

95 3. In a sole-channeling machine, a rotary feeding device for engaging the grain side of the sole, comprising a roll composed of a mass of abrasive material having a circular, unindented, abrasive, sole-engaging face and a circular support pressed against 100 one end of said roll having a smooth, non-abrasive, sole-supporting face continuous with the face of said roll, and adapted to engage the surface of the sole simultaneously therewith, substantially as described.

105 4. In a sole channeling machine a feeding device for engaging the grain side of the sole, comprising a rotary shaft, a roll secured thereon composed of a mass of abrasive material having an unindented cylindrical, sole-engaging face, and a metal support bearing against one end of said roll at its periphery and having a smooth, cylindrical, sole-engaging and supporting face continuous with the face of said roll, substantially 110 as described.

120 5. In a sole channeling machine a feeding device for engaging the grain side of the sole, comprising a shaft, a roll composed of a mass of abrasive material mounted on 125

said shaft and having a cylindrical, sole-engaging face, and metal disks clamped against opposite ends of said roll and having, at their peripheries, a smooth, cylindrical, sole-supporting surface, continuous with the sole-engaging face of said roll, substantially as described.

In testimony whereof, I have signed my name to this specification, in the presence of two subscribing witnesses.

EDWIN A. WEBSTER.
